CAN OPENER

Ernest J. Hileman and Michael J. Schuster,
Cleveland, Ohio

Application January 13, 1934, Serial No. 706,484

4 Claims. (Cl. 30—3)

This invention relates to an improvement in can openers of the type which uses a small rotating driving wheel to actuate a cutting tool causing it to travel around the top of the can.

5 One object of this invention is to provide improved means for piercing the can and locking the device on the can by means of a lever.

Another object is to provide a device that will remove the can top equally well whether 10 turned to the right or the left.

Further objects and advantages may be noted from the following specification and its accompanying illustrations, in which:

Fig. 1 is a front elevation of the device in 15 locking position.

Fig. 2 is a rear elevation of the device in locking position.

Fig. 3 is a side elevation showing the device in open position on a can.

20 Fig. 4 is similar to Fig. 3 but shows the device in locked position on a can.

Fig. 5 is a fragmentary view of the device showing the position of the device when handle is turned to the right.

25 Fig. 6 is similar view to Fig. 5 showing the position of the device when the handle is turned to the left.

Fig. 7 is a fragmentary view of a portion of the body of the device and the guide plate.

30 Fig. 8 is a sectional view of the handle, slide and driving wheel mounted on the body with a fragment of the lever and link.

Referring to the illustrations: The body 10 consists of a plate which has a slot 11 at the middle 35 of the bottom edge which widens into a round aperture 12 and ends in an elongated wide slot 13 near the top of the body 10.

The legs 14 and 15 formed by the slot 11 are 40 rolled at 16 and 17 to rigidly retain a pin 18 therein, and mounted pivotally upon said pin 18 is a link 19 folded as at 20 to receive a locking lever 21 when in locking position. The arms 22 and 23 formed by the fold 20 are attached by a pivot pin 24 to the locking lever 21 at the curved 45 portion 25 of said locking lever.

The upper end 26 of the locking lever is mounted pivotally on a pin 27 retained within a split hinge 28 at the base of a slide 29, said slide having a plurality of fingers 30 which embrace 50 the rounded edges of the body 10 in such manner as to give a smooth gliding movement as the slide is moved up and down by the toggle action of the lever 21.

55 Mounted rotatably within an aperture 31 in said slide 29 is a disc 32 to which is rigidly at-

tached a handle 33 by means of a shaft 34 which extends through the disc 32, and a small driving wheel 35 on the inner side of the body 10, said driving wheel being journaled upon said shaft with the driving wheel hub 36 against the disc 5 32 and slideable within the elongated slot 13.

A guide plate 37 with angularly projecting arms 38 and 39 is pivotally attached to the body 10 by a pivot pin 40 mounted through the body 10; a notch 41 in said guide plate 37 with a pin 10 42 mounted through body 10 limits the movement of the guide plate to the width of the slot. An elongated aperture 43 in said guide plate 37 prevents the guide plate binding on the rivet 44 which projects through the body 10. 15

A parting or cutting tool or blade 45 is superimposed over the guide plate 37 and retained rigidly in position by means of the pins 40 and 42 and the rivet 44. The lower portion of the parting or cutting tool is cut on an angle from 20 the center to form cutting edges 46 and 47.

In operation, the lever 21 is raised to the position shown in Fig. 3, the parting or cutting tool 45 is placed on the inside edge of the can 48 with the body 10 on the outside, the lever 21 is then 25 pulled down to the locking position against the can 48, this moves the slide 29 up on the body 10, thus drawing the driving wheel 35 against the seam 49 as shown in Fig. 4, the cutting tool 30 piercing the top of the can. The handle 33 30 when rotated to the left pivots the guide plate 37 to the position shown in Fig. 5 with the arm 39 bearing on the top of the can 48; if however, the handle 33 is rotated to the right the guide plate 37 pivots to the position shown in Fig. 6 35 with the arm 38 bearing on the top of can 48, and the turning of the handle in either direction causes the can to rotate on the driving wheel 35 and the parting tool 45 cuts the top from the can, using the cutting edge 46 when used as in 40 Fig. 6 but when used as in Fig. 5 the cutting edge 47 is used.

In locking the device to the can, the lever 21 is pushed down until the link 19 presses against the can 48, and the pivot pin 24 is thus inside 45 the center line of the pivot pins 18 and 27 which tends to hold the lever 21 in the locking position until released by an upward pull on said lever. The device will not release its hold upon the top of the can until the lever is moved upward to the unlocked position. The toggle action of the lever 21 and link 19 presses the slide 29 upwardly and pulls the body plate 10 downwardly, thereby engaging the wheel 35 with the 50 seam of the can and forcing the blade 45 into 55

the can top, after which rotation of the handle revolves the wheel 35 and the blade cuts out the top.

We claim:

- 5 1. A can opener comprising a slotted body plate adapted to be placed beside a can body, a slide movable up and down on said plate and provided with a blade arranged to cut the can top, a self-locking toggle comprising a link pivoted to the lower part of the plate and a lever pivoted to the link and the lower part of the slide, said toggle operating in the slot, and a rotatable feed wheel carried by the slide and arranged to engage the rim of the can.
- 10 15. 2. A can opener as in claim 1, the toggle link and lever being pivoted to swing in a plane perpendicular to the plane of the plate.
- 15 3. A can opener comprising a plate having a slot extending upwardly from the lower edge

thereof, and adapted to be placed beside the can body, a slide movable up and down on said plate, a feed wheel carried by the slide and having a bearing in the upper part of the slide, a depending blade mounted on the upper end of the 5 plate, and a toggle connected between the plate and the slide and working in the slot laterally to and from contact with the can body.

4. A can opener comprising a body plate, a slide thereon, a toggle lever and link connection 10 between the plate and slide, a blade carried by the plate and adapted to pierce a can top by the operation of the toggle, and a feeding wheel carried by the slide and arranged to engage the rim of the can to revolve the same, the plate having 15 a slot and the toggle being located to swing into said slot.
